UNITED STATES PATENT OFFICE.

ARTHUR L. BLUE, OF NEW YORK, N. Y.

PROOF-PRESS.

1,079,325.

Specification of Letters Patent.

Patented Nov. 25, 1913.

Application filed May 25, 1912. Serial No. 699,709.

To all whom it may concern:

Be it known that I, ARTHUR L. BLUE, a citizen of the United States, residing in the borough of Manhattan of the city of New York, in the county of New York, in the State of New York, have invented certain new and useful Improvements in Proof-Presses, of which the following is a specification, reference being had to the accompanying drawings, which form a part hereof.

Practically all large printing offices are equipped with proof presses for the purpose of taking off galley and job proofs before type are locked in the regular presses. Because of the desirability of keeping the face of the type in a perfectly flat plane, at least in the line of pressure of the impression roller, the bed-plates of such proof presses are usually made of heavy castings and the rest of the construction is correspondingly heavy. Moreover it has been thought necessary to provide rigid and consequently heavy supports for the impression roller, besides making the impression roller itself heavy. The consequence is that the proof presses are heavy, costly and not easily shifted from place to place as convenient use might suggest.

It is the object of this invention to provide a proof press which shall be light in weight and easily portable and at the same time shall permit a satisfactory proof to be taken either from a galley or job.

In the improved press the usual heavy cast metal bed-plate is replaced by a light weight bed-plate which may be made of any suitable material, such as sheet steel, and is supported upon suitable standards, and the frame is made to traverse the bed-plate having above the frame an impression roller and below the frame a reaction or pressure roller which, moving in contact with the bottom of the bed-plate and in parallelism with the impression roller, while the distance between the two rollers is maintained, supports the bed-plate, even though it may be somewhat yielding, and therefore the type in the line of printing with their faces in a plane parallel with the axis of the impression roller. The two rollers are preferably geared together and are actuated by a suitable crank on the axis of one of the rollers, so that the traverse of the printing frame is easily and quickly effected while the desired relation of the two rollers is maintained.

The invention will be more fully explained hereinafter with reference to the accompanying drawings in which it is illustrated and in which—

Figure 1 is a top view of a press constructed in accordance with the invention. Fig. 2 is a view of the same in side elevation. Fig. 3 is a view of the same in longitudinal section on the plane indicated by the line 3—3 of Fig. 1. Fig. 4 is a view of the same in transverse section on the plane indicated by the line 4—4 of Fig. 1 the rollers being shown in side elevation.

In the embodiment of the invention illustrated in the drawings a bed-plate *a*, which may be comparatively thin and light in weight, is supported on a suitable base *b* by legs or standards *c* and *d*. The standards *d* are preferably hinged to the bed-plate so that they may be turned up, as indicated by dotted lines in Fig. 2, to permit the removal of the printing frame, the legs being secured in normal position by convenient retaining devices, such as the swing bolts indicated at *d'*. On the longitudinal edges of the bed *a* are formed or secured, as by screws *a'*, shown in dotted lines in Fig. 3, rails or bearers *a''*, which are preferably slightly less than type high, so that job type can be locked up directly on the bed-plate or type can be locked up in a galley supported on the bed-plate and in either case the face of the type will rise slightly above the bearers.

The printing frame comprises two end plates or frames *e*, cross rods *f* which unite the end plates and hold them in rigid relation, an impression roller *g*, and a reaction or pressure roller *h*. The reaction or pressure roller *h* preferably consists of a rubber or other yielding body *h'* fixed on the shaft *h''* which is mounted in fixed bearings in the end plates or frames *e*. The impression roller *g* likewise consists of a rubber or other resilient body *g'* fixed on a shaft *g''* which is mounted in journal boxes *g''*. The journal boxes are mounted in vertical slots *e'* of the end plates or frames and may be pressed down, with the impression roller *g* toward the pressure roller *h*, by thumb screws *i* which are threaded in the upper ends of the end frames *e* and press upon the journal boxes through metal plates *i'* and yielding cushions *i''*, preferably of rubber. The shafts *g''* and *h''* preferably have intermeshing gears *g''* and *h''* fixed thereon, while one of the shafts, as *g''* may also have

secured thereto a suitable crank handle *k*. To each end plate or frame *e* may be secured a bracket *e*³ adapted to lie near the bearers *a*² and to prevent the frame from tilting 5 down if the impression roller *g* is raised or removed.

It will now be understood that when the type have been placed on the bed-plate, either directly or in a galley and have been 10 inked and the paper has been laid upon them, the crank *k* is actuated and thereby the printing frame, through the frictional contact of the pressure roller *h* against the underside of the bed-plate and of the impression roller *g* with the bearers, is caused 15 to traverse the bed-plate longitudinally. When the type are reached the pressure of the impression roller *g* is transferred from the bearers *a*² to the type, which stand 20 slightly higher than the bearers, and the movement of the printing frame is continued, the impression roller yielding sufficiently to enable a proper proof impression 25 to be secured. It will be observed that as the line of impression on the type face travels from one end of the job or galley to the other, the type in the line of impression are supported in proper relation 30 to the impression roller, with their faces parallel with the horizontal plane of the impression roller, through the reaction or pressure roller which supports the bed-plate across its entire width, and that this result 35 takes place even though the bed-plate is not absolutely rigid but yields slightly with the weight of the type or is slightly distorted from any other cause. The teeth of the gears *g*⁴ and *h*⁵ are sufficiently long to permit the necessary yielding movement of 40 one roller with respect to the other or the necessary adjustment of one roller with respect to the other. If it is necessary, at any time, to remove the printing frame from the bed-plate for the purpose of washing or repair, the legs or standards *d* may 45 be turned up to permit such removal.

It will be understood that the invention

is not limited to the precise details of construction and arrangement shown and described herein.

50

I claim as my invention:—

1. In a proof press, the combination of a yielding bed-plate to support the type, hinged means to support the bed-plate, a printing frame having a reaction or pressure roller having contact with the underside of the plate and an impression roller above the bed-plate and horizontal guide brackets carried on the frame in juxtaposition to the bed-plate, the rollers being movable over the hinged supporting means to permit the removal of the frame from the bed-plate. 55

2. In a proof press, the combination of a yielding bed-plate to support the type, longitudinal bearers less than type high secured on the upper face of the bed-plate, and adjacent the edges thereof, hinged means to support the bed-plate and a printing frame having a reaction or pressure roller for contact with the underside of the bed and an impression roller disposed on said bearers, the rollers being movable over the hinged supporting means to permit the removal of the frame from the bed-plate. 70

3. In a proof press the combination of a relatively thin and flexible bed-plate to support the type, means to support the bed-plate, a printing frame having a pressure roller having contact with the under side of the plate and an impression roller above the bed plate, the rollers being mounted yieldably with respect to each other, the flexible bed plate and yielding rollers compensating automatically for irregularities in the type as the line of impression changes thereby insuring a uniform impression throughout the proof. 80

This specification signed and witnessed this 23d day of May A. D., 1912.

ARTHUR L. BLUE.
